(57) **CLAIM**

The ornamental design for a drill press table, as shown and described.

DESCRIPTION

FIG. 1 is a front, top, left side, perspective view of a drill press table in accordance with my design;

FIG. 2 is a front elevation view thereof;

FIG. 3 is an enlarged fragmentary view of area 3 circumscribed within FIG. 2 with a piece thereof extended;

FIG. 4 is a rear elevation view thereof;

FIG. 5 is a left side elevation view thereof;

FIG. 6 is an enlarged fragmentary view of area 6 circumscribed within FIG. 5 with a part thereof extended;

FIG. 7 is a right side elevation view thereof;

FIG. 8 is a top plan view thereof;

FIG. 9 is a top plan view with a piece thereof extended;

FIG. 10 is a bottom plan view thereof;

FIG. 11 is a cross-section of the drill press table looking in the direction of line 11-11 of FIG. 4;

FIG. 12 is a cross-section of the drill press table looking in the direction of line 12-12 of FIG. 8;

FIG. 13 is a front, top, left side, perspective view of a second embodiment of a drill press table in accordance with my design;

FIG. 14 is a front elevation view thereof;

FIG. 15 is an enlarged fragmentary view of area 15 circumscribed within FIG. 14 with a piece thereof extended;

FIG. 16 is a rear elevation view thereof;

FIG. 17 is a left side elevation view thereof;

FIG. 18 is an enlarged fragmentary view of area 18 circumscribed within FIG. 17 with a part thereof extended;

FIG. 19 is a right side elevation view thereof;

FIG. 20 is a top plan view thereof;

FIG. 21 is an enlarged fragmentary view of area 21 circumscribed within FIG. 20 with a piece thereof extended;

FIG. 22 is a bottom plan view thereof;

FIG. 23 is a cross-section of the second embodiment of the drill press table looking in the direction of line 23-23 of FIG. 16; and,

(Continued)

FIG. 24 is a cross-section of the second embodiment of the drill press table looking in the direction of line 24-24 of FIG. 20.

The broken lines illustrate portions of the environment or drill press table which form no part of the claimed design. The dot-dot-dash lines surrounding the detail area in FIG. 2, FIG. 5, FIG. 14 and FIG. 17, and corresponding views in FIG. 3, FIG. 6, FIG. 15, and FIG. 18 depicts the boundary of the detail and forms no part of the claimed design.

1 Claim, 20 Drawing Sheets
